UNITED STATES PATENT OFFICE.

JOHN BELL SHELTON, OF EDSON, ALBERTA, CANADA, ASSIGNOR OF ONE-HALF TO
PETER DAVID, OF TACOMA, WASHINGTON.

FREIGHT OR CATTLE CAR.

1,094,485.

Specification of Letters Patent. Patented Apr. 28, 1914.

Application filed December 11, 1911. Serial No. 665,113.

To all whom it may concern:

Be it known that I, JOHN BELL SHELTON, citizen of the United States, residing at Edson, county of Edmonton, Province of Alberta, Dominion of Canada, have invented a certain new and useful Improvement in Freight or Cattle Cars, and declare the following to be a full, clear, and exact description of the same, such as will enable others skilled in the art to which it pertains to make and use the same, reference being had to the accompanying drawings, which form a part of this specification.

My invention relates to an improvement in freight or cattle cars, shown in the accompanying drawings and more particularly described in the following specification and claims.

It is well known that in shipping berries or other small fruits that their weight when piled above each other often results in crushing or otherwise damaging a large proportion of the fruit making it unmarketable. It is also well known that in shipping small live stock, such as sheep or hogs, in the usual form of cattle car that the full carrying capacity of the car is not taken advantage of, therefore one of the objects of this invention is to provide a refrigerator, cattle, or other freight carrying car with a movable platform or deck suspended from a manually rotatable shaft supported adjacent to its roof by suitable chains or cables passing over conveniently mounted pulleys, the arrangement being such that the platform may be lowered to divide the interior of the car on a horizontal plane, into two separate and distinct apartments, each of which is adapted for carrying small live stock;—the construction being such that the platform may be raised adjacent to the roof of the car by manually rotating the supporting shaft thereby putting the car in condition for carrying cattle or ordinary freight as in the usual manner.

Another object of my invention is to provide grain doors hinged to the movable platform,—the arrangement being such that one or both doors may be lifted by raising the platform to permit of the discharge of the grain from under the doors, avoiding the usual practice of breaking the grain door in order to unload the car;—the construction being such that when not in use for carrying grain the doors may be swung up under the

movable platform and supported by suitable engaging devices out of the way of the freight carried below.

Another object of the invention is to provide suitable supporting hooks on the underside of the movable platform from which may be suspended dressed meats, in order that by lowering the platform, the tendency of the car to be overturned when rounding curves due to the violent swinging of the meat, may be avoided;—it being well known that refrigerator cars as now constructed—with the meat suspended from the ceiling—are often derailed or overturned from this cause.

Another advantage is that the space above the platform from which the meat is suspended, may be occupied by other perishable merchandise.

Other advantages and improvements will hereafter appear.

In the drawings accompanying this specification: Figure 1 is a plan view of a car with the roof removed to more clearly show the construction of the parts. Fig. 2 is a substantially central longitudinal vertical section of the same. Fig. 3 is an end elevation with the parts broken away showing the means employed for rotating the winding drum. Fig. 4 is a substantially central longitudinal vertical section of a modification showing a grain door attached to the movable platform and in dotted lines the door slightly raised to discharge the grain. Fig. 5 is a central cross-sectional view of the car shown in Fig. 4. Fig. 6 is a fragmentary substantially central longitudinal vertical section of a car showing the platform provided with meat supporting hooks. Fig. 7 is a detail view of the supporting bracket secured to the carlines for supporting the winding drum. Fig. 8 is a sectional view through the bolts and shaft illustrating the vertically movable platform and the vertical sheaves and connections for suspending the platform.

Referring now to the letters of reference placed upon the drawings: A is a car.

B is a movable platform suspended by chains C from the rotatable shaft D, in turn supported by the carlines E, or the shaft may be journaled to the underside of the car frame in any other suitable manner.

C', C², are sheaves supported by the frame of the car, over which the chains C pass on

their way to the winding shaft D. Intermediate the chains C are chains C³ which have their respective ends connected to the platform B and are led over sheaves C⁴, these chains forming limiting means for the lowering of the platform B. The winding shaft D is preferably made up of sections d which may be of tubular form, bolted together as indicated at d'. The end sections 10 of the winding shaft D are provided with right and left hand screw shafts D².

F are traveling blocks to which are secured the end chains C.

G are guide rods spaced from the winding shaft D and projecting through apertures in the traveling blocks F,—the ends of the rods being supported in suitable members of the car frame. It will be obvious that the guide rods are employed to prevent 20 the rotation of the blocks F when traveling along the screw-threaded portion of the winding shaft.

H is a pinion mounted on the end of the winding shaft D, in mesh with a train of 25 gears H' adapted to be manually operated by the hand wheel H².

I are brackets or other suitable supporting means secured to the frame of the car, upon which the movable platform B may rest and 30 which may be located at any point on the frame to meet the requirements of the freight carried.

J are grain doors hinged at j to the underside of the movable platform B, as indicated 35 in Figs. 4 and 5 at j'. These doors may be detached from the platform by removing the hinge pintle j⁴ or the nuts j'; the platform may then be raised leaving the doors in position to close the opening into the car.

40 j² are suitable engaging devices carried by the movable platform adapted to support the grain doors beneath the platform when not in use. The movable platform may if desired be provided with a central opening 45 closed by a suitable trap door J' through which the lower compartment of the car may be loaded. Attached to the underside of the movable platform are a plurality of meat supporting hooks K from which dressed 50 hogs or other meat may be suspended, as shown in Fig. 6.

Having indicated the several parts by reference letters, the construction and operation of my invention will be readily understood. When it is desired to use the car as an ordinary freight, cattle, or refrigerator car, the platform may be raised adjacent to the underside of the roof of the car by manually operating the hand wheel H². If desired suitable engaging devices may be provided to secure the platform in its elevated position; these, however, are not shown as I have not found them essential. Assuming the device employed in connection with a 65 stock car adapted for carrying cattle, and it

is desired to haul small stock, the platform may be lowered to the position indicated in Fig. 2; stock may then be carried on each deck. When used in connection with an ordinary box car, the platform may be lowered 70 and different classes of freight loaded on each platform,—this arrangement will be found of particular advantage in shipping household furniture. When it is desired to use the box car to carry grain, the grain doors may be released and swung into position as indicated in Figs. 4 and 5, the car being loaded in the usual way,—through the trap door J', or the doors may be swung into position and disconnected from the platform 80 which may then be raised and the car filled, the grain entering above the doors and below the platform. The platform may then be lowered and the grain doors reengaged thereto. When it is desired to unload the 85 car, one or both of the doors may be raised (allowing the grain to be discharged below the grain doors) by manually operating the hand wheel H², as will be readily understood.

It will be apparent that my improvement 90 is of especial advantage in carrying small fruit or other perishable property as the freight may be placed on the different platforms thus relieving the goods below of excess weight due to being piled one on the other, as is necessary in freight cars as ordinarily constructed.

It is well known that in carrying dressed meats in refrigerator cars, when the meat is suspended in the usual way from hooks 100 secured to the ceiling of the car, that upon rounding curves the meat will swing from side to side which frequently results in the overturning of the car. By attaching the hooks to the underside of the movable platform, the platform may be lowered overcoming this tendency while the space above the platform may be occupied by other food products.

Having thus described my invention, what 110 I claim is:—

1. In a car of the character described, a movable platform, a winding shaft provided with a right and left hand screw-threaded portion, traveling blocks respectively engaging said screw-threaded portions, suitable sheaves for carrying a flexible element, a flexible element engaged to the platform and adapted to pass over the sheaves and connected with the traveling 120 blocks, and means for rotating the winding shaft whereby the traveling blocks may be operated and the platform raised or lowered.

2. In a car of the character described, an adjustable platform, grain doors hinged to 125 said platform, and means for raising and lowering said platform.

3. In combination, a car body having a door opening therein, a platform mounted for vertical movement within said car body, 130

- means to move said platform vertically, suspending means carrying the platform, and a door hinged to the platform and adapted to close said opening.
5. 4. In a car of the character described, an adjustable platform, meat supporting hooks carried by said platform, and means for raising and lowering said platform so that the meat suspended from said hooks may be 10 so positioned as to prevent swaying of the meat.
5. In a car of the character described, a winding shaft journaled in the car, a platform having connection with said shaft, 15 means whereby the shaft may be rotated to adjust the platform, a trap door formed in the platform, and grain doors having detachable hinged connection with the platform.
- 20 6. In a car of the character described, a shaft, a platform, flexible elements connected to the platform and to the shaft, means for rotating the shaft to take up and let out said chains so as to raise and lower the 25 platform, means for holding the platform in adjusted positions, grain doors hingedly connected to the platform so that they may be swung upwardly against the under side of the platform, means engageable with said doors to sustain them against the under side
- of the platform whereby the doors may be held sustained against the platform during adjustment of the latter, the hinge pintles of the hinged connections between the doors and the platform being removable so that 35 the platform may be raised and lowered without raising and lowering the doors.
7. In a car of the character described, an adjustable platform, detachable grain doors hinged to the platform, means for supporting said grain doors adjacent to the underside of the platform when not in use, and means for raising and lowering said platform.
8. In a car of the character described, an 45 adjustable platform, a winding shaft provided with right and left hand screw-threaded portions, traveling blocks mounted on said screw-threaded portions of the winding shaft, chains engaging said traveling blocks and connected with the platform, and means for rotating said shaft, whereby 50 the platform may be raised or lowered.

In testimony whereof I sign this specification in the presence of two witnesses.

JOHN BELL SHELTON.
